UNITED STATES PATENT OFFICE.

FORREST J. COUCH, OF ROCHESTER, NEW YORK, ASSIGNOR TO THE AMERICAN LAUNDRY MACHINERY COMPANY, OF CINCINNATI, OHIO, A CORPORATION OF OHIO.

PRESSING MACHINE.

Application filed August 18, 1916. Serial No. 115,658.

To all whom it may concern:

Be it known that I, FORREST J. COUCH, a citizen of the United States, residing at Rochester, in the county of Monroe and 5 State of New York, have invented certain new and useful Improvements in Pressing Machines, of which the following is a specification.

This invention relates to pressing machines, and more particularly to machines for pressing certain kinds of flat work, such as underwear and like wearing apparel. One common type of such machine comprises a stationary heated bed, a presser 10 member movable relatively thereto, and a work carrying device which is moved into position between the bed and presser for 15 the pressing operation.

One object of the invention is to provide 20 means for moistening the work prior to the pressing operation and for raising its nap after the pressing operation, for example, by applying a suitable moisture carrying medium, such as steam, thereto, in a manner 25 to improve the effect of the pressing members and obtain a superior finish. A further object of the invention is to provide moistening or steaming devices for the purposes described which operate conjointly with or 30 in proper sequence or relation to the devices for feeding the work to the machine and pressing it therein, thereby securing improved results or effects without extra care or effort by the operator.

35 Further objects of the invention are in part obvious and in part will appear more in detail hereinafter.

The invention comprises the pressing machine hereinafter described and claimed. 40 In the drawings, which represent one embodiment of the invention, Fig. 1 is a side elevation; Fig. 2 is an end view from the left in Fig. 1; Fig. 3 is a plan view; Fig. 4 is a side elevation of a portion of the 45 controlling mechanism; Fig. 5 is a sectional elevation on the line 5—5, Fig. 4; and Fig. 6 is a detail section of the steaming device.

The machine shown in the drawings, except for the added parts hereinafter more 50 fully described, is of the same form and construction as that shown in the patent to D. M. Cooper 1,139,346, granted May 11, 1915, to which reference may be had for a more complete disclosure. For present purposes 55 only a brief description of said machine,

as shown, is necessary. Referring to the drawings, the machine comprises a suitable frame 1 carrying a stationary heated bed 2, a co-operating movable presser member 3 and side rails or guides 4 to receive and support the movable work holders 5 upon which the work to be pressed is laid. Said rails extend in both directions endwise beyond the edges of the presser and bed and the work holders are moved along the same 60 from the feeding end of the machine to pressing position and then out at the delivery end. While all the machine operations may be manually and independently controlled the machine is preferably so organized 65 that the operation of a single controlling lever or device causes one complete cycle of operations of the machine, during which a newly filled work holder is fed into the pressing position, the previous work 70 holder is ejected, and the presser is moved into pressing relation with the bed and then returned to normal position ready for another pressing operation. The mechanism for effecting these operations will now be 75 briefly described.

Feeding devices.

The driving motor 10 is on a shaft 11 carrying a worm 12 driving a worm gear 13 on a sleeve 14 to which it attached a constantly rotating driving member 15. Said member may be connected, by the clutch devices to be described, to a shaft 16 carrying two crank arms 17 whose crank pins 18 80 work in slots in oscillating levers 19 connected by links 20 to followers or travelers 21 sliding in the guide rails 4. Whenever the clutch devices are actuated the shaft 16 turns through one complete revolution, 85 thereby producing both forward and backward oscillating strokes of the levers 19 and advance and retracting movements of the followers along the rails 4. Said followers engage the new work holder in position on 90 said rails and push it forward into pressing position, and the new work holder pushes out the one already in position between the 95 pressing members.

Clutch device.

For coupling the shaft 16 to the constantly rotating driving member 15 the latter is provided with clutch teeth or pins 22 in position to be engaged by a co-operating 100 105

clutch member 23 pivoted on a disc 24 pinned to shaft 16. Said clutch member is moved into clutching engagement with the pins 22 by a spring 25, but is normally held back by a stop device 26 carried by a shaft 27 to which is connected an arm 28 connected by link 29 to the foot treadle 30. Said treadle is provided with a counterweight 31 which normally holds the stop 26 in the position shown in Fig. 4, but when said treadle is depressed the stop device is withdrawn from engagement with the clutch member 23 which swings to clutching position and the next pin 22 coming around engages said device and rotates the shaft 16 until the stop 26, which has been released, again engages the clutch and disconnects the shaft from its driving member.

Presser movement.

The movable presser 3, to which the work holders are fed, is moved upwardly toward the bed by toggle links 35 actuated by a traveller 36 threaded on a screw 37 whose shaft 25 carries a gear 38 driven by a pinion 39 on the shaft of motor 40. The proper movement of the presser is obtained by controlling the circuits to said motor so as to cause it to rotate in one direction to advance the presser, to stop and hold the pressure, and to rotate in the other direction to retract the presser. These effects are produced by a suitable switch preferably operated or controlled by or in timed relation with the feeding devices, as will be described.

Motor switch control.

The motor switch has two contacts 41 connected by leads 42 to the motor, one of said contacts causing the motor to rotate in one direction and one in the other. Said contacts co-operate with a movable circuit closing contact 43 on a pivoted arm 44 connected by a link 45 to an oscillating arm 46 having yielding connection at 47 to an arm 48 provided with a pin or roller 49 in the path of movement of two oppositely inclined cams 50 on a cam wheel 51. Said wheel is loosely rotatable on a shaft 52 constantly driven through a worm 53 and worm wheel 54 from the constantly rotating sleeve 14. The cam wheel is connected at intervals to rotate with said shaft 52 by clutch devices similar in principle to those before described, and which it is unnecessary here to describe in detail, except that said devices include two tail pieces 55 engaged by a stop device 56 on an oscillating shaft 57 having an arm 58 whose end is in the path of movement of a lever 59 rotating with the shaft 16.

When shaft 16 is rotated the lever 59 engages the arm 58 and disengages the stop device 56 from the clutch tail piece 55, thereby closing the clutch and producing rotation of the cam wheel 51. This occurs when

the feeding device has delivered a new work holder into pressing position. The cam wheel rotates through half a revolution until stopped by the stop device 56, and during its movement actuates the switch device 70 to cause the motor to rotate in one direction to advance the presser, to stop and hold the pressure, and then rotate in the other direction to retract the presser.

Steaming devices.

The machine so far described is the same as that illustrated in the Cooper patent referred to. It remains to describe additional features required by the present invention. These comprise either or both of two conduits 60 lying opposite the end edges of the stationary bed and parallel therewith. Said conduits may be of any suitable form, but preferably are concaved slightly on their inner faces, as at 61, and provided with a long narrow slot or a series of spaced small ports or openings 62 in their upper inner portions adapted to discharge a cloud of steam or other moisture carrying medium 90 downwardly along the edge of the bed. The conduit itself serves as a guard to concentrate the steam cloud close to the bed while a shield or apron 63 extends from said conduit to the bed and also outwardly from the conduit, to further the concentration of the steam upon the work. The lobed bottom 60^a of the conduit forms a trap to receive and collect water of condensation and prevent it from dropping on the work, and said conduits are preferably provided with drain cocks 60^b. The conduits 60 are attached or connected to supply pipes 64 communicating with the hollow chamber 65 of the bed, which is heated by a steam supply through a conduit 66. In each pipe 64 is a valve 67 carrying a bracket 68 having a bearing for a rock shaft 69 extending across the bed from valve to valve, and provided with two arms 70 carrying adjustable screw abutments 71 lying above the valve stems 72. Shaft 69 also carries an arm 73 connected by a link 74 to one arm of a bell crank lever 75, whose other arm is connected by a link 76 to an arm 77 on a shaft 78 supported in a bracket 79 attached to the frame and provided with a second arm 80 having a roller 81 lying opposite a cam 82 fixed to the shaft 16. Said roller is held against its cam by a pressure spring 83 mounted in a pocket 84 of the lever 80 and a pocket 85 on the shaft supporting bracket.

The face of cam 82 is of such peripheral length, and said cam is so timed on its shaft 16 that when shaft 16 is rotated to start the feeding devices the lever and link mechanism described is operated to press the abutments 71 down upon the stems 72 and open the steaming valves. While the new work holder moves to pressing position a cloud 130

of steam is applied thereto, which moistens the goods preparatory to the pressing operation and secures improved results therefrom. The pressed goods on the work

5 holder being ejected are also subjected to a cloud of steam which mingles with the fabric and by rising therefrom at its high temperature raises the nap on the goods and generally improves their appearance.

10 Either steaming device may be rendered inoperative by screwing up its abutment screw 71 until it does not depress its valve stem, which may be taken advantage of for certain classes of work requiring only moistening before pressing or steaming after 15 pressing.

The frame is also provided with brackets 86 supporting two parallel tracks or guides 87, which may be angle irons with their 20 horizontal flanges extending inwardly. Said tracks extend from end to end of the machine and serve as a return device for the empty trays. They are inclined downwardly at the delivery end of the machine, 25 as at 88, and the operator, after taking off the work tilts the empty tray upwardly to engage the inclined track portions and pushes the tray back along the tracks. Each tray pushes along those ahead of it and 30 therefore enables the operator to return all empty trays to the feeding end of the machine to be refilled with work.

The steaming devices operate in timed relation with the work feeding and pressing 35 devices and steam the goods only while the work holders are moving to and from pressing position, although by suitable arrangement of the cam the steaming can be accomplished while the work holder is stationary, 40 but nevertheless before and after the pressing. While the work is being pressed, the roller 71 is at a low part of the can 80 and the steaming valves are closed. No extra care or effort of the operator is required but 45 the steaming is effected automatically by the movement of the mechanism.

What I claim is:—

1. The combination of platen type pressing members having relative vertical pressing movement, a work holder movable horizontally into and out of pressing position 50 between said members, means adjacent the edge of one of said members for directing moisture laden vapor upon the work on said holder, controlling means therefor adapted when operated to cause or cut off the supply of vapor to said means, and actuating means for said controlling means operating in timed relation with said movable work holder for causing the supply of said vapor as the holder moves to pressing position.

2. The combination of platen type pressing members having relative vertical pressing movement, a work holder movable horizontally into and out of pressing position 55

between said members, means adjacent the edge of one of said members for directing moisture laden vapor upon the work on said holder, controlling means therefor adapted when operated to cause or cut off the supply of vapor to said means, and actuating means for said controlling means operating in timed relation with said movable work holder for causing the supply of said vapor as the holder leaves pressing position. 70

3. The combination of platen type pressing members having relative vertical pressing movement, a work holder movable horizontally into and out of pressing position 75 between said members, means adjacent the edge of one of said members for directing moisture laden vapor upon the work on said holder, controlling means therefor adapted when operated to cause or cut off the supply of vapor to said means, and actuating means 80 for said controlling means operating in timed relation with said movable work holder for causing the supply of said vapor as the holder moves toward or away from pressing position. 85

4. The combination of pressing members having relative vertical pressing movement, a work holder having a rigid frame supporting a flexible sheet on which the work is carried, said work holder being movable 90 horizontally into and out of pressing position between said members, means for so moving said work holder, and means operating in timed relation with said work holder moving means for directing a stream 100 of moisture laden vapor upon the upper surface of the work on said holder as it moves to pressing position. 95

5. The combination of pressing members having relative vertical pressing movement, 105 a work holder having a rigid frame supporting a flexible sheet on which the work is carried, said work holder being movable horizontally into and out of pressing position between said members, means for so moving said work holder, and means operating in timed relation with said work holder, moving means for directing a stream 110 of moisture laden vapor upon the upper surface of the work on said holder 115 as it leaves pressing position.

6. The combination of pressing members having relative vertical pressing movement, a work holder having a rigid frame supporting a flexible sheet on which the work 120 is carried, said work holder being movable horizontally into and out of pressing position between said members, means for so moving said work holder, and means operating in timed relation with said work holder moving means for directing a stream 125 of moisture laden vapor upon the upper surface of the work on said holder as it moves toward and from pressing position.

7. The combination of pressing members 130

having relative vertical pressing movement, a work holder having a rigid frame supporting a flexible sheet on which the work is carried, means for moving said work 5 holder horizontally into position between said pressing members, and means operating conjointly with said work holder moving means for directing a stream of moisture laden vapor upon the upper surface 10 of the work upon said holder as it moves to pressing position.

8. The combination of pressing members having relative vertical pressing movement, a work holder having a rigid frame supporting a flexible sheet on which the work is carried, means for ejecting said work 15 holder from pressing position beneath said pressing members, and means operating conjointly with said ejecting means for directing a stream of moisture laden vapor 20 upon the upper surface of the work on said holder as it leaves pressing position.

9. The combination of platen type pressing members having relative vertical pressing movement, a work holder movable horizontally into and out of pressing position between said members, a hollow steam spraying conduit lying adjacent one edge 25 of the upper pressing member and adapted 30 to supply steam to the work upon said holder, means for supplying steam to said conduit, and controlling means for said steam supply operating in timed relation with the movement of said holder for supplying steam to the holder while passing 35 said conduit and cutting off said supply at other times.

10. The combination of pressing members having relative vertical pressing movement, a work holder, means whereby said 40 work holder may be moved horizontally from one side into pressing position between said pressing members and ejected from the opposite side of said members, two hollow conduits lying along adjacent 45 opposite edges of the upper pressing member for supplying steam downwardly upon the work on said holder, controlling means for permitting or cutting off the supply of steam to said conduits, and actuating means 50 for said controlling means operating in timed relation with the movement of said work holder.

11. The combination of platen type pressing members having relative vertical pressing movement, a work holder having a rigid frame supporting a flexible sheet on which the work is carried, means for moving said work holder horizontally from one side into position between said pressing 55 members and for ejecting said work holder from the opposite side of said members, two hollow conduits lying along opposite edges of the upper pressing member and arranged to direct two streams of steam 60 downwardly upon the work on said work holder, means for supplying steam to said conduits, and means operating in step with said work holder for controlling the connection of said conduits to the source of 65 steam supply.

In testimony whereof I affix my signature.

FORREST J. COUCH.
